UNITED STATES PATENT OFFICE.

EDWARD H. MCLOUD, OF COLUMBUS, OHIO, ASSIGNOR TO THE KINNEAR MANUFACTURING COMPANY, OF COLUMBUS, OHIO, A CORPORATION OF WEST VIRGINIA.

FIRE-SHUTTER.

1,204,802.

Specification of Letters Patent. Patented Nov. 14, 1916.

Application filed January 19, 1912. Serial No. 672,058.

To all whom it may concern:

Be it known that I, EDWARD H. MCLOUD, a citizen of the United States, residing at Columbus, in the county of Franklin and 5 State of Ohio, have invented a certain new and useful Improvement in Fire-Shutters, of which the following is a specification.

This invention relating more particularly to the class of rolling fire resisting shutters 10 that are closed by a dangerous rise of temperature, has for its object to prevent so violent a closing movement of such a shutter as might cause injury thereto and perhaps render it unfit to properly perform its 15 closing function.

The invention is embodied in the example illustrated in the accompanying drawings and set forth in the following description, the features of novelty being pointed out in 20 the appended claims.

Referring to said drawings which form a part of this specification Figure 1 is a longitudinal sectional view of the invention with parts appearing in full. Fig. 2 is a similar 25 view of a modification. Fig. 3 is a view in elevation of that end of the structure—being in the instance shown the right hand end—containing the means for holding the roller shaft of the corresponding end stationary, said means being in shaft-holding 30 position. Fig. 4 is a view similar to that of Fig. 3 showing the shaft-holding means released. Fig. 5 is a front view further illustrating the parts as they appear in Fig. 4. Fig. 6 is an end view of one of the clutching 35 collars.

In the said views and referring more particularly to Figs. 1, 3, 4, 5 and 6 the character 6 designates the barrel or drum to receive the rolling shutter, a fraction only of the latter being shown at 6^a. Said barrel 6 has fitted and secured in its opposite ends plugs 6^b and 6^c perforated to form journals for the shaft parts. The barrel is carried 45 upon a two-part shaft, the parts being designated 7 and 7^a, respectively, which in turn are supported in end brackets 8 and 8^a. The shaft part 7 has pinned on its end beyond the bracket a spur wheel 9 that is 50 engaged by a dog 9^a on swinging arm 10, said arm being held up to hold the shaft stationary by a wire 11 containing one or more connections 12 fusible by a dangerous rise of temperature. The wire 11 is pref-

erably extended to the short arm of a lever 55 13 having its other arm weighted.

The character 14 designates a weighted rod attached to a hinged arm 15 that supports the arm 10 in position to hold the dog 9^a engaged with the spur wheel 9. The release of the weighted rod 14 insures the release of the arms 15 and 10 when the fusible connection 12 is melted. The shaft part 7 has pinned to it near the end of the barrel a collar 16 to which is attached one end of a coil spring 17, the other end of said spring being secured to a plug 18 turning on the shaft part 7 but secured at its rim to the barrel. The coil spring 17 constitutes a tension member for normal operation of the 70 shutter. Said spring 17 is therefore secured so that the unrolling of the shutter increases its tension, the spring being preferably of such dimensions or power that when the parts are properly adjusted it 75 counterbalances the shutter for normal operation, that is to say, for winding and unwinding manually in normal conditions. The inner end of the shaft part 7 has pinned to it a clutch member 19 consisting of a 80 collar perforated to receive the end of the shaft-part 7, said collar being shown as having a disk-like head provided with a clutching projection 19^a.

The shaft part 7^a has upon its outer end 85 beyond the contiguous bracket 8^a a wheel 20 having one or more projections 20^a which can be engaged by a keeper 21 in the bracket to prevent said wheel and the shaft part 7^a 90 from turning after its adjustment, as hereinafter described, has been made. The shaft part 7^a within the barrel has pinned to it a collar 22 having a clutching lug or projection 22^a extending inward from its inner face. The inner end of the shaft part 7^a 95 (Fig. 1) is for convenience, shown to extend into the bore of the collar 19 and each can be turned with reference to the other. This construction also aids in alining the shaft parts with each other and in keeping them 100 alined. On the inner end of the shaft part 7^a are shown to be journaled two disk-like parts 23 and 24 each having on each of its faces clutching lugs or projections as seen at 23^a and 23^b and 24^a and 24^b. These parts 23 and 24 and their lugs are of such dimensions and so occupy the space between the 105 opposed faces of the collars 19 and 22 that

rotary motion of the collar 19 can be communicated to the collar 22 or rotary motion of the collar 22 to the collar 19 through the several lugs or projections on the collars and disks 23 and 24. But after all of said lugs have been placed into contiguity with each other by the rotation of one of said collars in one direction it requires several revolutions of either one of the parts in the opposite direction to bring them again into contiguity.

To adjust and fix the means thus described for the purpose stated the shaft-part 7 is held stationary while the shaft-part 7^a is turned so that the clutching lugs are in contiguity in a position that is the reverse of that in which they appear in Fig. 1 and until the shutter is nearly counterbalanced by the spring 17, when the said shaft-part 7^a is locked with the keeper 21. After this the shaft-part 7 is turned in a direction to increase its tension and quite counterbalance the shutter or so that the shutter will be held up and remain at the point to which it is raised or lowered when the said shaft 7 is locked by setting the lug 9^a or the means for releasing the shutter by a dangerous rise of temperature. It therefore follows that when the shaft-part 7 is released by a dangerous rise of temperature the shutter will descend by gravity and perhaps quite freely if the lugs of the clutching members and disks are not at the time in contiguity and then relatively slowly when said lugs come into contiguity because of the restraining effect of the spring on the drum engendered by the contiguity of the lugs, it being noted that the shaft 7 is held from rotation in the unwinding direction by the fixed shaft 7^a when said lugs are in contiguity. The restraining effect of the spring can be applied at any point desired by increasing or diminishing the number of disks or by changing the size of the contacting lugs but in practice the construction is preferably such that it is applied when the shutter being of ordinary dimensions is about one third of the way down so that it shall gently close and there will be sufficient counterbalancing effect to permit the shutter to be raised by those who might require to get into or out of the building through the opening closed.

In Fig. 2 the same construction is illustrated except that the shaft 7^a corresponding to 7^a of Fig. 1 is provided with a spring 25, the coil of which is the reverse of the counterbalancing spring 17, said spring being secured at one end to a collar 26 pinned on the shaft while the other end of the spring 60 is secured to a collar 22^b corresponding to the collar 22 of Fig. 1. In Fig. 2 the shaft corresponding to the shaft 7 of Fig. 1 is extended to the bore of the collar 26 and the disks 23 and 24 turn loose on said extension. 65 In other respects the parts illustrated in

Fig. 2 are substantially the same as illustrated in Fig. 1 and are correspondingly indicated. The function of the spring 25 is to cushion the blow of the lugs on the disks and clutching collars when the shutter is released. In other respects the mode of adjusting or preparing for operation the construction shown in Fig. 2 is substantially the same as that set forth with respect to Fig. 1. It is understood, of course, that the shutter can be made of any suitable length to close a window or door opening and that the parts are to be adapted to the particular opening for which they are designed to close.

Changes in the form and proportions of parts can be made, and some parts can be omitted and used in combination with others without departing from the gist of the invention.

What I claim is:

1. In a fire shutter, the combination with a rotary shutter receiving member, two shafts axially arranged in said shutter receiving member to support the same, means for fixing said shafts, a tension member between one of said shafts and the shutter receiving member for counterbalancing the shutter in normal operation, thermally controlled means for releasing said last named shaft, and a clutching member on each of said shafts, the clutching member on one shaft adapted to engage the clutch member on the other by rotation only upon the release of the shaft containing the tension member.

2. In a fire shutter, the combination with a rotary shutter receiving member, two shafts axially arranged in said shutter receiving member to support the same, means for fixing said shafts, a tension member between one of said shafts and the shutter receiving member for counterbalancing the shutter in normal operation, thermally controlled means for releasing said last named shaft, a clutching member on each of said shafts and a freely rotative clutch member between said clutch members to interengage them by rotation upon the release of the tension member.

3. In a fire shutter, the combination of a shutter and a shutter receiving member, a tension member for the normal operation of the shutter, means for releasing the tension member and shutter, and means including a freely rotative impact member within the shutter receiving member rendering said tension member reoperable to restrain the shutter after its release.

4. In a fire shutter, the combination of a shutter and a drum therefor, a two-part shaft for the drum, a spring connected with one of said shaft parts and with the drum, means releasably holding said shaft part, a clutch member on said shaft part, a clutch

member fixed on the other shaft part operably related to the first named clutch member and means whereby said second mentioned shaft part can be adjusted and held.

5. In a fire shutter, the combination of a shutter and a drum therefor, a two-part shaft for the drum, a spring connected with one of said shaft parts and with the drum, means releasably holding said shaft-part, a clutch member on said shaft-part, a clutch member fixed on the other shaft-part and movable means intermediate said clutch members permitting one clutch member to be operated by the other.

6. In a fire shutter, the combination of a shutter and a drum therefor, a two-part shaft for the drum, a spring connected with one of said shaft-parts and with the drum, means releasably holding said shaft-part, a clutch member fixed on the other shaft-part and a rotary disk provided with lugs located between said clutch members and adapted to be engaged by each of said clutch members.

7. In a fire shutter, the combination of a shutter and a shutter-receiving member, a tension member for the normal operation of the shutter, means for releasing the tension member and shutter, a clutching member and a cushioning member in connection with the shutter-receiving member adapted to be engaged by said clutching member after the release of the shutter.

8. In a fire shutter, the combination of a shutter and a drum therefor, a two-part shaft for the drum, a spring connected with one of said shaft-parts and with the drum, means releasably holding said shaft-part, a clutch member on said shaft-part, a second clutch member and a spring connecting said last named clutch member with a fixed part.

9. In a fire shutter, the combination of a shutter and a drum therefor, a two-part shaft for the drum, a spring connected with one of said shaft-parts and with the drum, means releasably holding said shaft-part, a second clutch member, a spring connecting said last named clutch member with the other shaft-part, and means whereby said last named shaft-part can be adjusted and fixed in adjusted position.

10. In a fire shutter, the combination of a shutter and a shutter receiving member, a tension member for the normal operation of the shutter, means for releasing the tension member and shutter, and means including a stationary and a coöperating freely rotative impact member within the shutter receiving member for rendering said tension member reoperable to restrain the shutter after its release.

11. A gravity fire shutter comprising in combination a drum, a shutter, a counter-balance means for said drum and shutter, clutch mechanism, and a controlling element for said mechanism operative to momentarily render said counter-balance means ineffective, said mechanism being entirely within said drum.

12. In a fire shutter, the combination of a shutter and a shutter receiving member, a tension member for the normal operation of the shutter, means for releasing the tension member and shutter, and means including a yielding and a coöperating freely rotative impact member within the shutter receiving member for rendering said tension member reoperable to restrain the shutter after its release.

EDWARD H. McCLOUD.
